UNITED STATES PATENT OFFICE.

HARRISON W. CONNER, OF BOSTON, MASSACHUSETTS.

WINDSHIELD FOR AUTOMOBILES.

Application filed September 25, 1919. Serial No. 326,301.

To all whom it may concern:

Be it known that I, HARRISON W. CONNER, a citizen of the United States, residing at Boston, in the county of Suffolk and State 5 of Massachusetts, have invented certain new and useful Improvements in Windshields for Automobiles, of which the following is a specification, reference being had therein to the accompanying drawing.

10 This invention relates to certain new and useful improvements in wind shields for automobiles, and more particularly to what is known in the art as tonneau wind shields the object being to provide a wind shield 15 which is exceedingly cheap and simple in construction and one which is capable of being folded in inoperative position and into operative positions.

Another and further object of the invention 20 is to provide a novel form of support which can be readily attached or placed in position within the body of the car in such a manner that the wind shield can either be supported in a rearwardly extended position 25 over the occupants of the rear seat or in a vertical position to the rear of the front seat, whereby the cable is being used in connection with a five or seven passenger car without interfering with the leg receiving 30 space.

A still further object of the invention is to provide novel means for retarding the 35 swinging of the frames and supported arms so as to prevent or relieve the shock, thereby preventing the glass or transparent material of the shield from becoming broken.

A still further object of the invention is to provide a wind shield in which a pair of 40 arms are detachably mounted in a pair of supports so constructed that the arms can be swung into horizontal position to support the wind shield frame in advance of the occupants of the rear seat.

Another and further object of the invention 45 is to provide a construction of wind shield and support which enables the supports to be connected by a guard in the form of a sheet whereby the wind shield when folded will be prevented from being injured by the occupants of the car.

Other and further objects and advantages 50 of the invention will be hereinafter set forth and the novel features thereof defined by the appended claims.

In the drawings:

55

Fig. 1 is a perspective view of a portion of an automobile showing the application of my construction of wind shield.

Fig. 2 is a vertical section showing the wind shield in raised position ready to be 60 lowered within the supports.

Fig. 3 is a detail perspective view of a slightly modified form showing the supports enclosed to form a housing, in order to prevent the transparent material of the wind 65 shield from being broken by the feet of the occupants of the car.

Fig. 4 is a detail vertical section showing my construction, the wind shield support formed integral in the front seat of the automobile.

Fig. 5 is a detail perspective view of a lock 70 hinge for holding the wind shield at any angle desired.

Figs. 6 to 20 are diagrammatic views illustrating various ways of constructing the 75 shield and support.

Fig. 21 is a perspective view of a modified form.

Fig. 22 is a vertical section through the 80 same.

Fig. 23 is a vertical section showing the shield folded.

Fig. 24 is a detail perspective view of the support, and

85

Fig. 25 is a detail plan view.

90

In the drawings, 1 indicates the body of an automobile, and 2, the front seat thereof as herein shown in dotted lines in order that the wind shield can be clearly shown. Secured within the body to the rear of the front seat 2, are supports 3 and 4, in the form of hollow posts which are substantially rectangular in cross-section. Mounted within the posts 3 and 4, are arms 5, said arms 95 being preferably mounted on detachable pins 6, which can be of the ordinary construction or in the form of a spring pin, said pin allowing the arms to swing on the arc of a circle into the positions shown in Figs. 1 and 2. The arms 5, are held in horizontal position by a shoulder 7, formed by notching the upper edge of the post and a lip 8, under which the free end of the arm extends in order to provide a rigid construction.

100

The ends of the arms 5 are provided with bosses 9, in which are secured bearing pins 10, on which are pivotally mounted the arms

105

11, of a wind shield frame 12, herein shown rectangular in form and provided with a pane of transparent material 13. While I have shown a single pane of transparent material in the drawings, I do not wish to limit myself to the nature or size of pane used as the frame might be divided so that a number of panes could be used without departing from the spirit of my invention.

10 The bosses 14 of the arms 11, carry spring actuated pins 15, which are adapted to register and extend into a series of openings 16, formed in the bosses 9 of the arms 5, in order to produce a lock hinge whereby the wind shield frame 12 can be locked in any desired position. The pins 15, are preferably provided with eyes and are connected together by a cable or chain 17, whereby the two pins can be operated in unison in order to allow the wind shield to be swung on its bearing so as to adjust the angle of the wind shield.

15 In order to provide means for retarding the swinging movement of the wind shield frame when released by the lock hinges in folding the wind shield, I provide arms 5 with hollow portions 18, in which are mounted plungers 19 and springs 20, said plungers 19 being connected to braces 21 by means 22 extending through slots formed in the walls of the arms 5, said braces 21 being pivotally connected to the wind shield frame as shown, and while I have shown a spring arranged within the chamber formed 20 in the arms 5, to the rear of the plunger, I do not wish to limit myself to the use of springs as the plungers and chambers may be constructed in the form of a dash pot so as to retard the movement of the plunger by 25 fluid without departing from the spirit of my invention.

30 By grasping the cable 17, the lock hinges will be released and by exerting a slight pressure on the wind shield frame the same will drop into folded position in such a manner that all danger of injury to the frame in any way is prevented as the swinging movement of the frame is retarded by the plunger traveling within the cylinder of the hollow arm.

35 The posts or supports 4, are provided with slots 4' through which extend braces 23, which are pivotally connected at their outer ends to the arms 5, and are pivotally connected to the plungers 24, mounted in chambers 25, formed in the posts. One wall of each chamber is preferably slotted in order to allow the pivot connection between the brace 23 and the plunger 24 to work 40 freely in the slot, whereby the plunger can be moved up and down within the chamber, and as shown, I arrange a coil spring 26 under the plunger for retarding the movement. It is of course understood that this 45 chamber could be formed like a dash pot

so that the fluid within the chamber would retard the movement of the plunger in a similar manner as disclosed in connection with the retarding means for the wind shield supports.

50 In Fig. 1 I show the wind shield frame extended rearwardly to the rear of the seat over the leg receiving space and when it is desired to use the construction in connection with a seven passenger car fully occupied, the wind shield frame is swung into alignment with the arms 5, and the arms 5 are swung into vertical position. The detachable pins 6, are then removed and the arms dropped into the supports 4, the downward movement of the arms by gravity being retarded by the plungers working in the cylinders or chambers. In this position the wind shield will be held in vertical position to the rear of the front seat. When the wind shield is in position shown in Fig. 1 by swinging into the position shown in dotted lines in Fig. 2 the arms and frame will be moved into such a position that a person can easily enter or get out of the car.

55 In the modification shown in Fig. 3, the construction of the wind shield and arms and supports are substantially the same with the exception that the supports are connected together by a sheet of metal or other suitable material 27, which provides a housing between the supports for the wind shield when in lowered position in order to protect the glass of the wind shield from the feet of the occupants of the car.

60 In Fig. 4, I have shown a similar construction embodied within the front seat of an automobile and comprising a construction substantially the same as shown in Fig. 3, the only difference being that the housing is formed as a unit of the car while in Fig. 3 the construction shown provides means for attaching the wind shield to any make of car.

65 In the construction shown in Figs. 6 to 20, I show various means of constructing the support and wind shield in order to retard the folding or swinging movement of the arms and frames so as to prevent the parts from being injured.

70 In Fig. 6 the support 28, is shown capable of being attached to the rear of the front seat of an automobile having arms 29, pivotally connected thereto by spring hinges 30, and the free ends of the arms 29, carry wind shields 31 which are connected to the arms by spring hinges 32, whereby the swinging movement of the arms and wind shield are retarded and while I have not illustrated any particular construction of spring hinge any form of spring hinge can be used which will retard the swinging movement of the frame and arms in order to prevent the parts from being injured.

In the Fig. 7, I have shown a support 33 formed hollow having a plunger 34 mounted therein connected to a sectional brace 35, which is provided with a brake joint and 5 is connected to an arm 36, which in turn is connected to the support by a spring hinge and carries a wind shield 37, connected thereto by a spring hinge.

In Fig. 8 I show a construction substantially as shown in Fig. 7, with the exception 10 that the arm is connected to the wind shield by a sectional brace 38, which is provided with a brake joint in order to allow the frame to swing in the direction shown by the 15 arrows.

In Fig. 9, I show a hollow housing 39, carrying an arm 40, which is mounted there-in substantially as in the same manner shown 20 in the preferred form. The arm 40, carries the wind shield frame 41, connected thereto by a spring joint 42, and in this construction means for retarding the swinging movement of the wind shield frame is provided 25 and the arms are allowed to drop into the posts or supports.

In the form shown in Fig. 10, a similiar construction is provided as that shown in Fig. 9, with the exception that the arm 42 carries a brace 43, provided with means 44, for retarding the movement of the arms in 30 lowering the same.

In the form shown in Fig. 11, I provide 35 a support 45, carrying arms 46, provided with a wind shield frame 47, having a brace 48 and in this form the brace can be detachably connected so as to allow the wind shield to fold.

In Fig. 12 the same construction of brace 40 is shown with the exception that an additional brace 49, is provided for the arm which in turn is connected to retarding means 50, mounted in the supports.

In Fig. 13 I show a hollow support 51, provided with a chain 52, in which is 45 mounted a plunger 53, which is connected to the supporting arm 54, by a cable 55, so constructed that when the detachable pins are removed so as to allow the arms to drop within the support, the weight of the plunger will retard the downward movement of the arms. While I have shown a plunger, it is of course understood as clearly 50 set forth in the specification that the spring or air can be used so as to retard the movement in order to accomplish the desired result.

In Fig. 14, a construction substantially as 60 shown in Fig. 13 is illustrated with the exception that the wind shield frame is connected to the arm by a brace 56 one end of which is detachably connected to its member so as to allow the shield to fold.

In Fig. 15 I show a construction substantially 65 as shown in Figs. 13 and 14, with the exception that the wind shield frame 57 is

provided with retarding means 58, in the nature of a plunger working in the supporting arm.

In Fig. 16 I provide a construction showing the same retarding means with the wind 70 shield frame as shown in Fig. 15, but I eliminate the retarding means shown in Fig. 15, a support 59 being constructed substantially the same.

In Fig. 17 I show a support 60, to which 75 is pivotally connected a supporting arm 61, which is connected to the plunger 62, by a brake joint brace 63 and the wind shield 64 is provided with a retarding means 65.

In Fig. 18, as shown in Fig. 17, the supporting arm 66 is pivotally connected to the support 67, in such a manner that the arm 80 folds downwardly against the support and the wind shield frame 68, is provided with retarding means 69, and in this construction 85 the connection between the supporting arms and support can be in the form of a spring hinge which will retard the swinging movement of the frame.

In Fig. 19, the same construction is shown 90 with the exception that a brace 70, is employed having a connection with a plunger 71 mounted in the support.

In Fig. 20 I provide a support 72, having 95 a chamber to receive the plunger 73, which is connected to the support and arms 74 by a brace 75 in the wind shield frame 76, which is provided with retarding means 77.

In the various forms shown in Figs. 6 to 20, I have attempted to illustrate and 100 describe different means of carrying out my invention, as one main object of my invention is to provide means for mounting the 105 arm and wind shield in such a manner that the movement of the arms and wind shield will be retarded, so as to prevent injury to the parts in raising and lowering the shield as with the construction of retarding means herein shown and described, the swinging 110 movements of the arms and frames in either direction is retarded, whereby the wind shield and arm can be moved into operative or inoperative position without injuring the parts in any way, and while I have not illustrated the details of construction of some 115 of the modified forms for carrying out my invention, I reserve the right to construct and to employ any and all forms of retarding means for a tonneau wind shield. While in the preferred form I have shown certain 120 details of construction, I do not wish to limit myself to this detail construction and I reserve the right to make any and all changes without departing from the spirit of 125 my invention as clearly defined in the appended claims.

In the construction of the tonneau wind shield illustrated in Figs. 21 to 25, I show 130 the supporting arms provided with a shield forming a protection for the wind shield

when in lowered position within the tonneau of the car. In these figures suitable supports in the form of brackets 78, are secured to the back of the front seat of the motor vehicle, which brackets are preferably formed with bolts 79, for securing the same firmly in position, as clearly shown in Figs. 22 and 23. The brackets 78 have spaced arms 80, between which are mounted supporting arms 81, said arms being adapted to extend rearwardly under the body portion of the bracket in order to hold the same in horizontal position when extended as shown in Fig. 21. The arms 81 are mounted on detachable pins 82, which may be in the form of spring actuated pins so that they can be withdrawn in order to allow the arms to assume a vertical position and drop down through the bracket as shown in Fig. 25. When the arms 81 are in horizontal position, they are supported by a shoulder 83, and while in this form of support I have failed to show braces for supporting the arms 81, it is of course understood if desired braces could be used. The arms 81 carry a wind shield frame 84 constructed substantially the same as shown in the preferred form of my invention, which wind shield frame is pivotally mounted on the arm which is provided with lock 30 hinges for holding the same in adjusted position. In the preferred form of the drawing, I showed a wind shield frame formed of a single section, but stated that the same could be formed of any number of sections 35 desired and it is well known in the art that tonneau wind shields are formed of three sections, as clearly shown in Fig. 1. The main or central section 84 of the wind shield carries adjustable wings or sections 85, which 40 are capable of being extended outwardly at any angle desired and locked by the wing nut 86, or folded against the main section as clearly shown in Fig. 23.

In Fig. 21, I have shown the shield attached to a tonneau of a five passenger car and in position to be used on such a style of car, but it is of course understood that the same could be used in connection with a seven passenger car and when so used, the 50 arms are swung upwardly and lowered into the position shown in Fig. 22, so that the shield will be directly back of the front seat of the vehicle.

The arms 81 are connected together by a 55 sheet of thin metal 87, which is secured to the under side of the arm as clearly shown in Figs. 24 and 25, and is provided at each end with a substantially U-shaped rib 88, forming a channel so as to allow the same to work around the free end of one of the arms 60 80 of the support 78, as clearly shown in Fig. 25. This shield protector 87 also forms a guard over the foot receiving portion of the tonneau when in use as shown in Fig. 21, and when the arms are moved into vertical

position and lowered through the brackets into the position shown in Fig. 23 with the wind shield sections folded, the glass of the wind shield is protected from the feet of the occupants of the car, so that all danger 70 of same becoming broken is prevented.

In all the figures of the drawings, I have shown the tonneau wind shield carried by a pair of arms mounted on supports carried by or arranged to the rear of the front seat 75 of the motor vehicle in such a manner that the wind shield sections can be folded and the arms folded so as to occupy very small space to the rear of the front seat.

From the foregoing description, it will 80 be seen that I have provided a wind shield which is formed of a pair of supporting arms pivotally and slidably mounted in supports in such a manner that the same can be folded or adjusted into various positions 85 within the tonneau of the motor vehicle, the supporting arms of the wind shield and wind shield frame being so connected together that retarding means is provided for preventing the parts from being injured when 90 being placed into inoperative or operative position, and while I have shown certain details of construction for accomplishing this result, I do not wish to limit myself to any particular means as the main object of my 95 invention is to provide means for retarding the swinging movement of the arms and the swinging movement of the wind shield frame in connection with means for protecting the wind shield frames when in lowered position. 100

I claim:

1. A tonneau wind shield comprising supports, arms pivotally and slidably mounted in said supports, detachable pins upon which said arms are pivotally mounted, said arms being capable of sliding in said supports when the detachable pins are removed and a wind shield frame pivotally mounted on the free ends of said arms. 105

2. A tonneau wind shield comprising 110 hollow supports, arms pivotally and slidably mounted in said supports, detachable pins upon which said arms are pivotally mounted, said arms being capable of sliding in said supports when said pins are removed, a wind 115 shield frame pivotally mounted on the free ends of said arms and means for retarding the swinging movement of said frame.

3. A tonneau wind shield comprising a 120 pair of supports, a pair of supporting arms pivotally connected to said supports, a wind shield frame pivotally connected to said supporting arms, means for locking said wind shield frame in adjustable position on said arms and braces connecting said wind 125 shield frame to said arms having a connection with means for retarding the swinging movement of said wind shield frame.

4. A tonneau wind shield comprising 130 spaced supports, arms pivotally and slid-

ably mounted in said supports, a wind shield frame carried by said arms, a guard connecting said supports forming a housing in which said wind shield frame is capable of being moved and means for retarding the movement of said arms in said frame.

5. A wind shield comprising a pair of supports, arms pivotally and slidably mounted in said supports, a wind shield frame pivotally carried by the free ends of said arms, braces connecting said wind shield frame to said arms, braces connecting said arms to said support and means for locking said wind shield frame in adjusted position on said arms.

6. A wind shield comprising a pair of supports, a pair of arms pivotally and slidably mounted in said supports, said supports being provided with chambers, plungers mounted in said chambers, a brace connecting said plunger to said arms, and a wind shield frame pivotally carried by the free ends of said arms.

7. A tonneau wind shield comprising a pair of supports, arms mounted in said supports on detachable pins and capable of sliding into vertical position and swinging into horizontal position when released from said pins, a wind shield frame carried by the free end of said arm and braces connecting said wind shield frame to said arm.

8. A wind shield comprising a pair of supports, detachable pins mounted in said supports, arms slidably mounted in said supports, said arms being pivotally mounted on said detachable pins, a wind shield frame carried by the free ends of said arms, means for locking said wind shield frame in adjustable position, and means for retarding the swinging movement of said wind shield frame and arms.

9. A wind shield comprising a pair of supports, detachable pins mounted in said supports, arms pivotally mounted on said pins, means for holding said arms in horizontal position, said arms being capable of dropping into the supports when the detachable pins are removed, a wind shield frame carried by the free ends of said arms and braces connecting said wind shield frame to said arms, and said arms to said supports having a connection with sliding means for retarding the swinging movement of said arms and frame.

55 10. A tonneau wind shield comprising a pair of arms pivotally and slidably connect-

ed to the body of the car, means for holding said arms in horizontal position, a wind shield frame pivotally carried by the free end of said arms, means for locking said wind shield frame in adjusted position on the ends of said arms, means for retarding the swinging movement of said frame when released by said locking means, and means for retarding the downward movement of said arms when released from said detachable pins.

11. A wind shield comprising a pair of supports adapted to be connected to the body of a motor vehicle, detachable pins carried by said supports, arms pivotally mounted on said detachable pins and capable of dropping into vertical position when released by said pins, means for retarding the downward movement of said arms when released by said pins, and an adjustably mounted wind shield frame carried by said arms.

12. A wind shield for motor vehicles comprising a pair of posts adapted to be secured within the body to the rear of the front seat, said posts being provided with chambers, a pair of arms pivotally and slidably mounted in said supports, plungers mounted in said chambers, braces connecting said plungers to said arms, said arms being provided with chambers, plungers mounted in chambers of said arms, a wind shield frame connected to the free ends of said arms and braces connecting the said wind shield frame to the plungers of said arms.

13. A wind shield comprising a pair of supports, detachable pins mounted in said supports, arms slidably mounted in said supports, said arms being capable of being pivotally mounted on said detachable pins, a wind shield frame carried by the free ends of said arms and means for retarding the sliding movement of said arms in said supports.

14. A tonneau wind shield comprising a pair of supports, a pair of arms pivotally and slidably mounted in said supports and a wind shield frame pivotally mounted on the free ends of said arms, said frame being capable of being folded between said arms to allow said arms to move vertically within said support.

In testimony whereof I hereunto affix my signature.

HARRISON W. CONNER.
